COMBINED HOPPER AND BUNK FEEDER

Floyd E. Buschbom, Rte. 1, Long Lake, Minn.

Filed June 8, 1962, Ser. No. 70,484

Term of patent 14 years

(Cl. D55—1)

FIG. 1

FIG. 2

FIG. 3

FIG. 4

FIGURE 1 is a perspective view of the front of one side of a combined hopper and bunk feeder, showing my new design;

FIGURE 2 is a side perspective view thereof with the conveyor element broken away for convenience of illustration.

FIGURE 3 is a perspective view of the rear and one side of a combined hopper and bunk feeder showing my new design.

FIGURE 4 is a plan view thereof with the conveyor element broken away for convenience of illustration.

I claim:

The ornamental design for a combined hopper and bunk feeder, as shown.
